Attorney

UNITED STATES PATENT OFFICE.

CHARLES W. CRUM, OF OLNEY, ILLINOIS.

BOTTLE-BRACKET.

1,215,495.

Specification of Letters Patent. Patented Feb. 13, 1917.

Application filed April 21, 1916. Serial No. 92,652.

To all whom it may concern:

Be it known that I, CHARLES W. CRUM, a citizen of the United States of America, residing at Olney, in the county of Richland and State of Illinois, have invented new and useful Improvements in Bottle-Brackets, of which the following is a specification.

The present invention relates to improvements in bottle brackets for use in connection with school desks and seats for retaining an ink bottle in place on the top of a desk.

In general the object of the invention is to provide an efficient durable, and inexpensive device for use in schools or other places for retaining and protecting an ink bottle on the top of the desk or other article of furniture, and more particularly the object of the invention is the production of a simple bottle retaining bracket which may be applied with facility to the supporting object, as the back of a school chair, and which will be simple in construction and adaptation for use.

The invention consists in certain novel combinations and arrangements of parts involving the back of the chair, the desk top, the bottle and the bracket as will be more fully pointed out and claimed hereinafter.

In the accompanying drawings I have illustrated one complete example of the physical embodiment of my invention constructed according to the best mode I have so far devised for the practical application of the principles of my invention. It will be understood that minor changes or alterations are contemplated in the practical application of the bracket, and these and all other colorable changes are included within the scope of my claim.

Figure 1 is a perspective view of the bracket made according to my invention.

Fig. 2 is a view in elevation showing the bracket attached to the back of a school chair and retaining an ink bottle in place on the top of a desk.

Fig. 3 is a transverse vertical sectional view of the bracket on line 3—3 of Fig. 2.

In the preferred embodiment of my invention as illustrated in the drawings I have utilized the conventional form of chair or seat back A and indicated the desk top as B, and it will be understood that in many, if not the majority of schools, the back of the chair to the front of the desk, projects at least two inches above the top surface of the

desk. My invention is particularly adapted to meet this condition and the bracket 1 is shown as attached to the rear of the top portion of the chair back to retain and protect 60 the ink bottle C.

The bracket, as a whole, is designated by the numeral 1 and is preferably made up of sheet metal stamped into shape as required, and of comparatively light, but strong and durable construction. The bracket is fashioned with a front plate 2, rectangular in outline, and provided near its ends with a pair of vertically extending slots 3, 3'. A top plate 4, formed with a central orifice or opening 5, is bent at an angle to the front plate 2. In the present instance the angle of the two plates is slightly beyond 90 degrees in order to adapt the plate to the inclined back of the chair. It will readily be understood of course that the plates may be bent to different angles to adapt the bracket for different uses or supports. The top or retaining plate 4 lies in a horizontal plane parallel with the desk top B and the bottle 80 C of course rests upon the top with the orifice 5 fitting about the neck D of the bottle.

Preferably the retaining plate 4 is formed with vertical sides or depending flanges 6, 85 three in number, which, as will readily be seen fit down over the top corners of the bottle body. While I have illustrated the retaining top plate and flanges as forming a rectangular device it will readily be understood that the portion composed of the top plate and flanges may be circular for instance, to fit a round bottle, or other shapes or forms may be adopted to adapt the device for different shaped bottles, or ink wells. 90 95

The bracket is attached to the back of the chair or other article of furniture by the utilization of the two securing or clamping screws 7 7, or, preferably these screws may be supporting screws for the bracket 100 and the third screw is then used as a lock screw. All the screws are passed through the slots in the plate 2 and are threaded into the back of the chair A in order that the bracket may be supported with stability. As best seen in Fig. 3 the plate 2 is bent at an angle to the top plate 4 so that it fits neatly in snug contact with the back of the chair. The screws are located in position so that they are accessible for a screw driver above 110 the top of the desk in order that they may be manipulated with facility, and it will

readily be seen that by unscrewing the screws the bracket may be quickly detached from the back of the chair if such action is required. In applying the bracket to the bottle C, the bracket after having been attached, loosely, to the back of the chair by the application of the screws, may be lifted until the bottoms of the slots contact with the screws 7 7. With the bracket thus lifted the bottle C may be slipped into position directly under the center of the opening 5 in the plate 4, and then when the bracket is lowered the orifice 5 slips over the neck of the bottle resting on the top as seen in Fig. 3, and the flanges 6 fit snugly about the body of the bottle. The screws 7 may then be clamped against the plate 2 and in this manner the bottle is held or retained in fixed position. If desired the third screw 7' may be

utilized to lock the parts. It will thus be seen that it is impossible to knock over, or spill the ink from the bottle; the bottle is held rigidly so that noise or rattle because of movement is eliminated, and is sanitary.

What I claim is:—

A bracket comprising a pair of angularly disposed plates one being elongated and formed with a slot near each end and screws in the slots securing the bracket to a support, and the other plate having an opening to fit around the neck of a bottle, and flanges depending from the edges of this plate to fit over the body of the bottle, said opening being located in position so that the slotted plate will coöperate with the flanges to hold the bottle stable.

In testimony whereof I affix my signature.
CHARLES W. CRUM.
